COMBINED FOOTSTOOL AND FOOT EXERCISER

Forrest E. Correll, Box 893, Lake Arrowhead, Calif.

Filed Aug. 13, 1962, Ser. No. 71,261

Term of patent 14 years

(Cl. D83—5)

FIG. 1 is a perspective view of a combined footstool and foot exerciser showing my new design, the undisclosed side being substantially the same as the side shown;

FIG. 2 is an enlarged top plan view thereof; and

FIG. 3 is an enlarged elevation thereof as seen from the opposite end of FIG. 1.

The characteristic feature of my design for the combined footstool and foot exerciser resides in the specific configuration of the support leg members, as shown.

I claim:

The ornamental design for a combined footstool and foot exerciser, as shown and described.
